UNITED STATES PATENT OFFICE.

FRANCIS E. J. WILDE, OF MEADOWMERE PARK, NEW YORK, ASSIGNOR TO MOTOGRAM CORPORATION, OF NEW YORK, N. Y., A CORPORATION OF NEW YORK.

ELECTRIC-SIGN CONTROL.

Application filed March 24, 1926. Serial No. 96,910.

This invention relates to the operation and control of electric signs, particularly those of the type in which the lights on a board are flashed to produce the effect of traveling letters or other symbols. These effects are usually produced by traversing patterns of the desired outlines past a bank of switch devices connected to control correspondingly located lights on the sign board. Such signs have been restricted in their scope by the number of sign characters which it has been possible to maintain in circulation.

Special objects of the present invention are to increase the scope or usefulness of such signs by enabling practically any number of sign characters to be maintained in circulation and further, to permit increase or decrease or changing of the sign characters while the operation continues so that the reading of the sign may be varied either as to length or information conveyed without interrupting operation of the same.

Other objects of the present invention are to simplify and improve the structure of the sign patterns, the switch devices, the conveyer for the patterns and other related parts.

The novel features of construction, combination and relation of parts by which the foregoing and other desirable objects are attained are set forth in the following specification and illustrated in the accompanying drawings which show a few of the at present preferred embodiments of the invention.

Figure 1 is a general side elevation of the complete machine, the travel of the sign characters being indicated in broken lines.

Figure 2 is an enlarged broken sectional view of the switch devices illustrating the actuation of the same by the traveling sign patterns.

Figure 3 is a cross sectional view of the switch bank as on substantially the plane of line 3-3 of Figure 2.

Figure 4 is a detail view of one of the individual terminal posts with its flexible brush for circuit completing contact with the traveling sign element.

Figure 5 is a fragmentary vertical section

of one of the letter magazines with the conveyer chains for extracting the letters therefrom.

Figure 6 is a sectional view transversely of the chains as on substantially the plane 55 of line 6-6 of Figure 5.

Figures 7 and 8 are broken, front and side views respectively of a modification in which the lugs for propelling the pattern plates are formed as integral extensions of 60 the chain links.

Figure 9 is a fragmentary vertical section of a modified switch structure having flexible contacts arranged in pairs and adapted to be bent together by patterns of insulating 65 material.

Figure 10 is a horizontal sectional view as on substantially the plane of line 10-10 of Figure 9.

Figure 11 is a broken plan of one of the 70 metal contact strips with attached contact fingers.

Figure 12 is a sectional view of the same as on line 12-12 of Figure 11.

Figure 13 is a plan of one of the metal 75 letter patterns.

Figure 14 is a plan of one of the insulating letter patterns.

Figure 15 is a plan of a stencil form of insulating pattern plate. 80

Figure 16 is a sectional view of the latter as on the line 16-16.

Figure 17 is a broken detail of a rocker actuated form of switch mechanism.

Figure 18 is a broken side elevation of 85 the machine as designed with a horizontal instead of a vertical contact block.

Figures 19 and 20 are face and sectional views showing a form of cast metal letter on an insulating backing secured to a metal 90 carrier plate, Figure 20 taken as on line 20-20 of Figure 19.

Figures 21 and 22 are similar views of another form of stencil plates, arranged with offset, overlapping edges. 95

Figure 23 is a broken part sectional side elevation of a form of the machine designed to take sign characters selectively from different magazines.

Figure 24 is a part sectional detail of the 100

special inclined post and brush construction which may be employed.

Figure 25 is a view illustrating in plan how the pattern plates may be guided over 5 rods, instead of by magazine walls, the rods appearing in section.

In Figure 1 a typical sign board is illustrated on a reduced scale at 1 having lights 2 connected by wiring 3 with the correspondingly located controls in the bank of switch devices 4. This bank is shown supported by suitable framing 5 in position for actuation by vertically traveling sign characters. This relation conserves space, but it will be understood that this control bank may be mounted horizontally or inclined, depending on circumstances.

Some of the sign characters are indicated at 6, Figure 1, traveling upwardly through 20 a guide 7 in position to actuate the switch devices, located in the paths of these particular outlines. The pattern guide has a rearwardly directed elbow 8 at the top by which the patterns, after actuating selected 25 switches are directed through a return way 9 to the top of a collection receptacle or magazine 10. Entering this magazine, the pattern plates are reversed or turned over by the cooperating inclined guides 11, 12 so 30 as to bring the raised patterns 13 on the plates lowermost.

From the bottom of the stack in the magazine 10, the patterns are extracted one at a time by means consisting in the present disclosure of sprocket chains 14 having horizontal runs supported in channel guides 15 below the foot of the stack and provided with opposite inwardly extending lugs 16, Figures 5 and 6, engaging behind the transverse ribs or runners 17 extending across the faces, near the side edges of the sign plates.

From the foot of magazine 10, the sign characters are carried by the chains upwardly through a curved and vertically extending guideway 18 and dropped face down into the top of a supplemental magazine 19, the latter being effected by carrying the chains over and downward about guide sprockets 20, the patterns being guided and 45 confined by an enclosing hood 21 opening into the top of magazine 19 and an inclined guide 22 directing the plates face down as they fall in the magazine.

From the top of the second magazine 19, 55 the chains extend downwardly over guide sprockets 23 and thence forwardly beneath the foot of said magazine, extracting one by one the bottom patterns in the stack after the manner described with respect to the 60 first magazine.

The sign characters thus extracted from the foot of the second magazine 19 are carried upwardly by the chains through a 65 guide passage 24 and deposited face down in the top of a third magazine 25 by guide

devices similar to those described at the top of magazine 19.

From the third or final magazine 25 the sign characters are extracted by the horizontal runs of the sprocket chains and carried one by one upwardly through a curved or inclined way 26 into the guide 7 which holds them in operative relation to the switch devices.

A single set of chains may be utilized as 75 shown to carry the sign characters between successive magazines and past the bank of switch controls. The same set of chains also may be employed to carry the characters from the switch controls back to the first receiver or magazine 10 as by extending the return runs 27 of the chains through the return way 8, 9 and over the top of the chute and thence by guide sprockets 28, 29 to the main drive sprockets 30. These main sprockets are shown operated by an electric motor 31 and suitable reduction gearing 32. In case of extra long lengths of chain, other drive motors may be provided, as for example, at the sprockets 23 at the foot of magazines 19 and 25.

By using a plurality of magazines, capacity for a relatively large number of sign plates is provided in a machine of compact design and the weight of the stack of characters is kept so low that the chains can easily pull out the lowest character without undue friction. To accommodate a greater number of the plates in the same overall height, one or all of the magazines may be set on a slant or incline, the lower ends of the same sloping forwardly in the direction of feed so that the plates will slip out easily and naturally from the foot of the pile, as shown at 10 in Figure 18.

The inclined magazine has the further advantage that the rearward walls of such magazines have a tendency to support the edges of the plates and thus take part of the weight off the lower plates, allowing those to slide out more easily. If desired, also, the return way 9 may be inclined downwardly to the rear to effect or facilitate return of the plates to the first receiver. The several chutes or magazines may be placed 110 one behind the other as closely as the shape of the guides 26, 24, 18 will allow.

The magazines, guides and propelling chains constitute means for maintaining a continuous circuit of the sign characters 120 past the control board, which may be kept in operation to reiterate selected advertising matter at the sign board. If desired, however, the advertising or other matter may be varied while the machine is in operation, for instance, by abstracting certain of the characters and substituting others in place of the same. The characters, for instance, may be removed from the return way after 125 they leave the control board or the return 130

runs 27 of the chains might be utilized to return all the characters either into selected classified magazines or into a common receiver. New characters could then be inserted in circuit, for instance, in the first magazine 10 which may be of open structure to disclose the characters, the latter being marked so that they can be easily identified. Also, the magazines may be made detachable as units which can be readily removed and be replaced. It is further in the contemplation of this invention that selected characters may be placed in circuit by a keyboard action after the manner of a type setting machine so that the reading matter may be constantly changed, for instance, to provide a news bulletin.

The sign characters may be of conducting or non-conducting material. In the first example, Figures 1 to 6 and 13, metal characters 33 are shown mounted on insulated backings 34 on the plates 6. These metal characters are connected by branches 35 with charging strips 36 extending entirely across the plates and adapted to be engaged by a special charging brush 37, Figure 3, connected by wiring 38 with one side of the source of energy 39.

The lamps 2 of the sign board are connected by the wires 3 with the individual insulated terminal posts 40. These posts, as shown in Figure 4, have flexible brushes 41 at their inner ends which make wiping engagement with the charged letters or sign characters.

To establish the proper contact making relation between the brushes and the traveling sign characters, relative adjustment may be provided, as shown in Figure 3, by constructing the rear section of the frame 5, the part which carries the upright chain guides 7 as a laterally shiftable section which can be adjusted by the screws 42, with respect to the outer or fixed section 43 which carries the terminal posts.

If non-conducting or insulating sign characters are used, as shown at 44 in Figure 14, then the circuit arrangement such as shown in Figures 9 to 12 may be employed where individual terminal posts 45 for the different lamps or groups of lamps have flexible brush ends 46 adapted to be engaged by flexible contacts 47 when the latter are bent upward by a passing insulating character.

The contacts 47 are indicated in Figures 11 and 12 as spring tongues inserted through loops 48 in a base plate 49, being secured in such loops by bent lugs 50. This forms a comb structure in which all fingers of one row are electrically connected and the comb is charged by having bent out lugs 51, Figure 10, at the ends of the back plate, engaged behind overstanding rails or cleats 52, the latter being charged by wiring 53 from one

side of the current source 39. Strips of insulation 54 are interposed between each comb and the companion row of terminal contacts 46, these strips being narrow enough to permit the longer contacts 47 to bend into engagement with the shorter contacts 46 and wider strips of insulation 55 in back of the combs prevent the spring fingers 47 from snapping backward into engagement with an adjoining row of terminals 75 when released by the passing sign characters.

In place of the switch devices described, switches of the push button type may be employed, as indicated in Figure 17, where at 56 is shown, one of the individual lamp terminals engageable by a contact head on the plunger 57 which is acted on by a spring 58 to interrupt the circuit and is shifted in the reverse direction by one arm of a bell-crank lever 59 pivoted at 60 and whose opposite arm 61 is positioned for actuation by the traveling sign character.

The principle of the stencil also may be employed, as indicated in Figures 15, 16, where the character plate 6 is shown as having the outline of the character cut there-through as a stencil 62. In this case, a charged plate 63 is placed in back of the traveling stencils to be contacted by the spring brushes which are in the line of travel of the slots or openings in the stencil plates.

The driving lugs on the chains may be varied to suit different conditions. Thus, in Figures 7 and 8 these lugs are shown provided by equipping certain of the inside links of the chains with inwardly extending angular projections or flanges 64 which are disposed so as to engage the rearward edges of the sign plates 6.

In Figure 18, the general plan of operation is the same, but the first magazine 10 is set on a downward, forward incline, the control block is disposed horizontally, extending forwardly from the foot of the second magazine 19 and made up in individually removable sections 65, the characters drop into a receiving magazine 66 at the forward end of the switch panel and are carried by separate chains 67 up through a guide 68 to the head of the return way 9 which slopes downwardly to return the plates by gravity.

Figures 19 and 20 illustrate a cast metal letter 33 removably attached to its insulating backing 34 by screws 69 extended through lugs 70 at the ends of the letter, said backing removably attached to the supporting plate 6 by screws 71, the supporting plate having cutouts 72 to prevent the letter securing screws 69 from contacting the same. In these illustrations the charging strip 36 serves also as a supporting runner corresponding to the one shown at 17.

Figures 21 and 22 show how the pattern

plates, stencils in this case, may be formed with offsets 73 at their edges, permitting them to overlap in closely engaged relation.

5. Figure 23 illustrates one way in which the characters may be taken selectively from different magazines 74, 75, 76, removably and interchangeably engaged in sockets or holders 77 over the runway leading to the 10 control board, the action of any one of them being controlled by a valve 78, governing passage down through the holder. In this structure the brushes 79 are inclined in the direction of travel of the letters and, as 15 shown in Figure 24, may be made as easily removable slip springs held by surrounding square insulating sleeves 80, over the projecting shanks of the square terminal posts 81. The tips of these brush springs are 20 shown rounded at 82 in the direction of travel so as not to scrape or scratch the letters. These brushes further are shown bowed at 83 to form a spring interlock between the holding sleeves and posts and as 25 having angularly turned inner ends 84 which hook against the inner ends of the insulating bushings or sleeves enabling the sleeves to force the brushes down into place over the posts.

30. The magazines may be of skeleton form and may consist simply of guide rails as indicated at 85 in Figure 25 entering corresponding guide slots 86 in the edges of the character plates.

35. What is claimed is:

1. In apparatus of the character disclosed, sign elements, a series of magazines for said sign elements, a guideway for the sign elements and means for conveying said sign 40 elements successively from one magazine into another and through said guideway back into the first magazine.

2. In apparatus of the character disclosed, sign elements, a series of magazines for said 45 sign elements, a guideway for the sign elements, means for conveying said sign elements successively from one magazine into another and through said guideway back into the first magazine and switch devices positioned adjacent said guideway and adapted to be selectively operated by the sign elements traversing the same.

3. In apparatus of the character disclosed, sign elements, a series of magazines for said 55 sign elements, a guideway for the sign elements and means for conveying said sign elements successively from one magazine into another and through said guideway back into the first magazine, said sign elements bearing the outlines of readable characters and switch devices positioned adjacent the guideway and actuated selectively according to the outlines of successive sign elements traversing the guideway.

60. 4. In apparatus of the character disclosed,

a control panel, magazines positioned one behind the other in rear of said panel, sign characters in said magazines and means for traversing said sign elements successively from one magazine to another and from the 70 magazine nearest the control panel to and past said control panel.

5. In apparatus of the character disclosed, a control panel, magazines positioned one behind the other in rear of said panel, sign 75 characters in said magazines and means for traversing said sign elements successively from one magazine to another and from the magazine nearest the control panel to and past said control panel, said means including devices for returning the sign characters from the control panel back to the magazine furthest in rear of the same.

6. In apparatus of the character disclosed, sign characters, a succession of magazines 85 and chains for successively conveying said sign characters from one magazine into another and thence from said latter magazine.

7. In apparatus of the character disclosed, switch devices, a guideway extending past the same, sign characters for traversing said guideway, a succession of magazines and means for traversing the sign characters from one magazine into another and from said magazines through the guideway past 90 the switch devices.

8. In apparatus of the character disclosed, a control panel containing switch devices, a guideway extending past said panel, sign 100 characters for traversing said guideway and means for relatively shifting said guideway and control panel to effect relative adjustment of the sign characters traversing the guideway and the switch devices of the control panel.

9. In apparatus of the character disclosed, a control panel, sign characters for cooperation with the same, a magazine for said characters, a guideway extending from the magazine to the control panel, a return way extending from the control panel to the magazine and a single set of propelling chains for carrying the sign characters from the magazine through the guideway past the control panel and through the return way 115 to the magazine.

10. In apparatus of the character disclosed, sign elements, a series of magazines for holding different groups of said sign elements, a guideway for the sign elements and means for conveying said sign elements from the different magazines through said guideway.

11. In apparatus of the character disclosed, sign elements, a series of magazines for holding different groups of said sign elements, a guideway for the sign elements, means for conveying said sign elements from the different magazines through said guideway and sign controlling switch devices as 125 130

sociated with said guideway and selectively operable by different sign elements from the several magazines.

12. In apparatus of the character dis-
5 closed, sign control switch devices, sign pat-
terns for selectively actuating the different
switch devices, a plurality of magazines for
holding said patterns stacked in different

groups and means for automatically extract-
ing the patterns from one magazine and for ¹⁰ carrying same past the switch devices to a
different magazine.

In witness whereof, I have hereunto set
my hand this 19th day of February, 1926.

FRANCIS E. J. WILDE.
